UNITED STATES PATENT OFFICE

CHRISTOPHER EDMUND GERVASE BAILEY, OF LONDON, ENGLAND, ASSIGNOR TO
VICTOR TALKING MACHINE COMPANY, A CORPORATION OF NEW JERSEY

TUNING DEVICE FOR WIRELESS RECEIVERS

Application filed January 6, 1930, Serial No. 418,930, and in Great Britain January 9, 1929.

The present invention relates to the tuning devices of wireless receivers in which it is desired to tune two or more separate circuits by means of "ganged" or mechanically interconnected controls.

In a supersonic heterodyne receiver, for example, in which a frame aerial is used, the frequencies of the oscillator and the main tuning circuits are connected by the relation that there must be a constant difference between them, namely the so-called "intermediate" frequency. If tuning condensers are used for tuning these two circuits with the blades so shaped that the angular movement of the dial is a linear function of the frequency, there will be a constant difference between the angular positions of these condensers when the set is in tune, provided that the same angular position of both of them corresponds to the same frequency. If the condensers are similar, this last condition is only fulfilled if the inductance of the frame aerial circuit is equal to the inductance of the oscillator coil, and if there is no distributed capacity in the circuit not allowed for in the shaping of the condenser blades. If these conditions are fulfilled, the two condensers may be operated from a common shaft.

The second condition cannot in practice be fulfilled, and it is usual to provide a small compensating condenser in one of the circuits for the final tuning adjustment.

According to the present invention, in a wireless receiving circuit embodying two or more tunable circuits with interconnected controls, a compensating device in the form of a variable inductance is provided in or coupled to one or more of said tunable circuits. It will be clear from the above description of the usual form of supersonic heterodyne receiver that, when the present invention is applied to these receivers, the setting of the compensating device may remain substantially constant throughout the range of the tuning condensers. In practice it may, however, be found necessary to vary the adjustment of the compensating device over the lower 10% of the tuning range.

The variable inductance may either be of

small value in series with the main inductance or one of large value in parallel therewith.

Alternatively, the value of the main inductance may be altered, for example by inductively coupling thereto another inductance of small value forming a closed circuit, such as a single loop of wire or a metal sheet, the coupling being made adjustable.

The invention is illustrated by way of example in the accompanying drawing.

In both the circuit arrangements in the drawing the invention is shown applied to a supersonic heterodyne receiver embodying a valve acting simultaneously as first detector and oscillator.

Figure 1 of the drawing is a diagrammatic view of a preferred embodiment of my invention, and

Figure 2 is a diagrammatic view of a circuit including an alternative form of my invention.

Referring to Fig. 1 of the drawing, a frame aerial 1 has connected in series with it a small variometer 2 and the whole is shunted by a variable tuning condenser 3. One terminal of the tuned circuit 1, 2, 3 is connected through a fixed condenser 4 to the mid-point of a grid circuit inductance 5 which is shunted by a second variable tuning condenser 6 which is mechanically coupled to the first variable condenser 3, and the other terminal of the tuned circuit 1, 2, 3 is connected to the filament of a thermionic valve 7. One end of the inductance 5 is connected through a high resistance 8 to the filament of the valve 7 and the other end of the inductance 5 is connected to the grid of the valve 7. The anode of the valve 7 is connected through an inductance 9, coupled to the grid circuit inductance 5, to a source of high tension supply 10, the negative terminal of which is connected to the filament of the valve 7.

The coupling of the two inductances 5, 9 is so arranged as to produce oscillations of the valve 7. The remainder of the circuit may be arranged in any known or suitable manner. In Fig. 2, the variable inductance 2 is shown arranged in series with the grid

circuit inductance 5 instead of in the aerial circuit, other connections being the same as in Fig. 1.

In a modification of the above arrangements the variometer 2 is omitted and, instead, a relatively large variometer is connected in shunt with either the frame aerial 1 or the grid circuit inductance 5.

I claim:

10. 1. In combination, a thermionic oscillator having an input inductor provided with tuning means, a receiving network provided with tuning means, a connection including a reactor between one terminal of said network and an intermediate point on said input inductor, means for simultaneously adjusting both of said tuning means to provide a substantially constant frequency difference, and a compensating device in the form of a variable inductor associated with at least one of said tuning means.

20. 2. In combination, a thermionic tube, an input inductor therefor, terminals of said inductor being connected, respectively, to the grid of said tube and to the cathode thereof, a resistor in said last-named connection, tuning means for said inductor, a receiving network provided with tuning means, a connection including a reactor between one terminal of said network and an intermediate point on said input inductor, means for simultaneously adjusting both of said tuning means to provide a substantially constant frequency difference, and a compensating device in the form of a variable inductor associated with at least one of said tuning means.

30. 3. The invention set forth in claim 2 characterized in that the compensating device is associated with the input inductor.

40. 4. The invention as set forth in claim 2 characterized in that the compensating device is associated with the receiving network.

50. 5. In combination, a frame aerial, a variable inductor connected in series therewith, a tuning condenser connected in shunt thereto, a thermionic tube having an input circuit, an input inductor therefor, a tuning condenser connected in shunt with said input inductor, a connection including a fixed condenser between a point on the frame aerial and an intermediate point on said input inductor, mechanical coupling means interconnecting said tuning condensers, and a connection from another point on said frame aerial to the cathode of said thermionic tube.

60. 6. The invention as set forth in claim 5 characterized in that one terminal of the input inductor is connected directly to the grid of the thermionic tube and the other terminal of the said input inductor is connected to the cathode of the said thermionic tube through a resistor.

70. 7. The invention as set forth in claim 5 characterized in that means are provided whereby energy from the output circuit of

said tube is transferred to the input circuit thereof to cause the generation of oscillations.

8. In combination, a frame aerial, a tuning condenser connected in shunt thereto, a thermionic tube, an input inductor for said tube, a tuning condenser connected in shunt to said input inductor, means interconnecting said tuning condensers for simultaneous operation, a connection including a coupling condenser between a point on said frame aerial and an intermediate point on said input inductor, a further connection from another point on said input inductor to the cathode of said tube, and a compensating variable inductor serially included in the circuit constituted by said input inductor and the tuning condenser connected in shunt thereto.

9. The invention set forth in claim 8 characterized in that one terminal of said input inductor is connected to the cathode of said tube over a resistor.

10. The invention set forth in claim 8 characterized in that means are provided whereby said tube is caused to generate oscillations.

In testimony whereof I have signed my name to this specification.

CHRISTOPHER EDMUND GERVASE BAILEY.
